UNITED STATES PATENT OFFICE.

ABRAHAM NOVICK, OF FLUSHING, NEW YORK, ASSIGNOR TO F. L. SMITH MACHINE CO., INC., OF NEW YORK, N. Y., A CORPORATION OF NEW YORK.

WEB PERFORATING AND FOLDING MECHANISM.

Application filed June 16, 1927. Serial No. 199,285.

This invention relates to the formation of packs of folded material, and more particularly to means for forming packs from superimposed plies or webs of suitable material, 5 such as paper, with flat folds so that each pack will be compact and of substantially the same thickness throughout.

The general object of the invention is to provide means for forming such flat compact 10 packs, which means are effective in operation, simple in structure and economical to manufacture.

Another object of the invention is to provide pack-forming means in which a plurality of superimposed plies of material are 15 perforated along transverse lines at suitable intervals, and cross-folded in flat folds, first in one direction and then in the other at successive lines of perforation so as to lie flat 20 in the resulting pack.

The invention will be understood from the following description taken in connection with the accompanying drawings in which

Fig. 1 is a top plan view of the main portion of a machine embodying one form of the invention;

Fig. 2 is a longitudinal sectional view in a plane perpendicular to the plane of Fig. 1;

Fig. 3 is a detail view illustrating two jaws 30 and parts for operating the same;

Fig. 4 is a sectional view illustrating the position of certain parts as a blade and presser member come together to form a transverse row of perforations, the jaws being retracted;

Fig. 5 illustrates the relation of the parts when they have advanced far enough from their positions in Fig. 3 to permit the jaws to close;

Fig. 6 is a view taken along the line 6—6 of 40 Fig. 2, parts being broken away to show the underlying structure;

Fig. 7 is a view taken along the line 7—7 of Fig. 2;

Fig. 8 is a detail view on a larger scale 45 of a portion of a perforating blade;

Fig. 9 is a view illustrating the formation of a pack as the material passes down through the perforating and folding means;

Fig. 10 is a fragmentary view on a larger 50 scale illustrating the appearance of the edge of a fold as seen from above;

Fig. 11 is a fragmentary view showing on a larger scale the material after perforation

along a transverse line but in extended condition; and

Fig. 12 is a view showing the plurality of superimposed plies with transverse lines of perforations but in extended condition.

Referring to the drawings, it will be seen that in carrying out the invention according 60 to the illustrative embodiment of the pack-forming means, the material 15 in the form of a web or a plurality of superimposed webs of paper, for example, is fed downwardly between feed rolls 16 and 17 to and through perforating and folding mechanism by which the material is perforated first from one side by a toothed blade 18 engaging the material at that side and forcing it against a presser member 19 on the opposite side, which serves 70 as a platen or anvil, and the material is then gripped on opposite sides of the blade and folded thereover by jaws 20 at opposite sides of member 19, which jaws also hold the folded material during the separation of the knife 75 and member and swing the material to one side for pack-forming, and then are operated to release the material.

The same operation is then effected with the arrangement of the blade and presser 80 member reversed and such operations are repeated alternately at opposite sides of the material to produce flat folds, thereby facilitating the cross-folding of the web and the collection of the various sections in flat folded form in a compact pack on a support below the perforating and folding mechanism as illustrated in Fig. 9. Ordinarily the mere folding of a plurality of superimposed webs or plies produces a pack or pile which is 90 thicker at the edges where the folds appear than between such edges. In forming such packs or piles according to the present invention, however, the provision of lines of perforations at the fold lines enables flat folds 95 and compact packs to be obtained and particularly so in view of the pressing action of the jaws 20 at said fold lines.

As illustrated in Figs. 1 and 2, the perforating and folding mechanism comprises 100 two shafts 21 and 22 having reduced ends journaled in side bars or members 23 and 24 of a frame including ends 25 to retain the side members in fixed relation. Mounted on the shafts 21 and 22 are two gears 26 and 27 respectively which mesh with each other and

are of the same size and shape so as to cause the rotation of the shafts 21 and 22 at equal speeds in opposite directions. The actuation of these shafts may be effected by applying power to shaft 21.

As here shown, each shaft 21 and 22 carries one blade 18 and one platen or anvil 19 at opposite sides of the shaft and these knives and blocks are so arranged that when the shafts are rotated, as indicated in Fig. 2, a blade carried by one shaft will engage the corresponding platen carried by the other shaft and this action will be reversed when the shafts have turned through 180°. At each perforating operation, the material 15 is folded and as the folds are effected alternately from opposite sides, and the material is swung from side to side, the material tends to form, as illustrated in Fig. 9, a compact, flat-folded pack. It should be understood that a plurality of blades 18 and a plurality of blocks or anvils 19 may be provided for each of the shafts 21 and 22, and that a suitable rate of feed of the material may be obtained by rotating the feed or guide rolls 16 and 17, at a surface speed corresponding to that of the knives and platen strips.

Each knife 18 is mounted in a bar 28 of which the ends are guided for radial sliding in grooves 29 at the inner sides of members or bars 30 on one of the shafts 21 and 22 and the platen or anvil 19 of the corresponding shaft is mounted in a bar 31 slidably guided in grooves 32 at the inner faces of the bars 30 and at the ends opposite to those carrying the knife 18. Jaws 20 are provided at opposite sides of each of the bars 31 and are pivoted in the bars 30, these jaws being formed with engaging portions arranged to extend around the outer edge of the bar 31 for engagement beyond the outer face of the platen or anvil 19. Each platen is in the form of a relatively narrow strip and may be of any suitable material such, for example, as celluloid which is sufficiently resilient and presents a surface which is not easily broken by the teeth of the perforating blade.

The pivoting of the jaws may be effected by pivots 33 integral therewith and operatively connected together by gears 34 thereon adjacent one bar 30, and at the other end of the jaws one of the pivots 33 may be provided with an arm 35 connected by a tension spring 36 with an arm 37 projecting from the corresponding bar 30 so as to enable the application of the tension of the spring 36 in the proper direction to close the jaws. Mounted on the other pivot 33 adjacent the same bar 30 is a curved cam or arm 38 by which the jaws may be opened by engagement with pins 39 and 40 projecting from a member 41 attached to the bar 23.

As shown in Fig. 2, the blade 18 carried by the shaft 22 has already acted against the platen 19 on the shaft 21 and the material

has been folded by the jaws 20 adjacent this platen and withdrawn from such blade 18. Upon further rotation of the shafts 21 and 22 in the directions indicated, the jaws 20 on the shaft 22 will be opened by engagement 70 of the arm 38 with the pin 39 and the blade 18 on the shaft 21 will be engaged by the platen or anvil 19 carried by the shaft 22, thus producing a line of perforations across the material 15.

As the shafts continue to rotate, the cam or arm 38 will ride off the pin 39 as indicated in Fig. 5 and the jaws 20 will swing together beyond the block 19 to fold the material over the edge of the blade 18. As the shafts 21 and 22 continue to operate the blade 18 will be withdrawn from the jaws 20 as indicated in Fig. 9, the fold of the web remaining however in the grip of the jaws 20. As, however, the shafts continue their rotation, the material will be shifted somewhat to the right by the jaws until the cam or arm 38 engages a pin 40 and the jaws are again moved apart to release the fold of material gripped therebetween. During further rotation of the 90 shafts 21 and 22, the cam or arm 38 will ride off the pin 40 and the jaws will close and remain in such condition until the corresponding cam or arm 38 again engages the pin 39. Upon further rotation of the shafts 21 95 and 22 the blade 18 mounted on the shaft 21 will engage the platen 19 mounted on the shaft 22 and the operation will be repeated in exactly the same way except that the fold in the material will be in the opposite direction. 100

It will be evident that the bars 30 and the two shafts 21 and 22 must be so positioned that each blade 18 will engage the platen or anvil carried by the other shaft. To assure such cooperation between the knives and blocks, it is desirable to provide some means for angular adjustment. To this end each shaft is provided as indicated in Fig. 2 with depressions 42 adapted to receive the inner ends of screws 43 threaded through the corresponding bars 30. It will be apparent that by loosening one screw and tightening the other, a slight relative rotation of each arm 30 on the shaft 21 may be produced. The arms 30 on the shaft 22 may be adjusted in position thereon in the same manner. 110

As each knife 18 strikes the corresponding platen or anvil 19 there may be side pressure on the blade 18 and to avoid the possibility of trouble resulting therefrom, each blade 18 is mounted in a groove of greater width and thickness than the blade and the rear edge of the blade rests in a narrow groove in which position it is held by means including a set of screws 44 passing through the rear wall of the member 28 and through perforations in the blade 18 and threaded into the bar 28. Mounted on the shank of each of these screws 44 is a helical spring 45 interposed between 125 the blade 18 and threaded into the bar 28. 120 Mounted on the shank of each of these screws 44 is a helical spring 45 interposed between 130

the head of the screw and the blade 18 to hold the latter in proper position while permitting yielding thereof when required.

It will be evident that the blades 18 and the blocks 19 must be adjusted carefully to obtain suitable engagement throughout their lengths and to this end each bar 28 is provided with a series of screws 46 screwed into the rear edge thereof but having their heads resting against the shafts 21 or 22 as the case may be, so that by turning the screws in one direction or the other the proper adjustment may be obtained. Such adjustment of the screws 46 may be maintained by means of lock-nuts 47. The setting of the screws 46 merely determines the minimum spacing of the bar 28 from the shafts but outward movement of the bar may be prevented by means of screws 48 passing through slots 49 in the bars 30 and 20 threaded into the bar 28. Obviously, by tightening the screws 48 after an adjustment, the bar 28 will be clamped in adjusted position. Adjustment of each bar 31 may be obtained in the same general manner by supporting screws 50 provided with lock-nuts 51 and by clamping screws 52 extending through slots in the bars 30 and threaded into the ends of the bar.

Preferably the teeth 18^a of each blade 18 are rather broad and have relatively narrow gaps therebetween, as indicated in Fig. 8, and the perforated material 15, which may include a plurality of superimposed plies 15^a, appears in extended form as indicated in Figs. 11 and 12, and in folded form as indicated in Fig. 10. It will be evident that the paper, when perforated as indicated in Figs. 10 and 11, will be connected across the fold lines only by narrow strips 15^b and these strips will offer very little resistance to folding along such fold lines thus enabling a much sharper and flatter fold to be obtained than by former methods.

Cross folded packs of superimposed webs of paper are of value for different purposes, as for example in making simultaneously a plurality of copies of an invoice or statement, and a flat-folded pack such as obtained by carrying out the present invention is especially advantageous in that it is compact and therefore does not require so much space, and furthermore is not liable to become disarranged.

It should be understood that various changes may be resorted to within the scope of the invention and that portions of the improvements may be used without others.

Having thus described my invention, I claim:

1. A device of the class described including means for forming at a single station successive flat perforated folds alternately in opposite directions in a multiple-ply web fed downwardly therethrough, and means for causing the material passing downwardly

from said forming means to collect in cross-folded pack form.

2. A device of the class described including means for forming at a single station successive flat transverse perforated folds in superimposed webs of paper alternately in opposite directions, and means to guide said webs into position for action thereon by such fold-forming means.

3. In combination, means for perforating a multiple-ply web at a plurality of points in each of a succession of transverse lines across the web, and means for creasing said web into a flat fold along each line of perforation concomitantly with the perforating action and alternately in opposite directions.

4. In combination, a toothed device, a platen member to cooperate with said device to perforate along transverse lines superimposed webs passing through the device, means for moving said device and platen members toward and from each other, and folding means for engaging said webs on opposite sides of a line of perforations substantially at the time the perforating is effected and forming a flat fold at said line.

5. In combination, two frames rotatable about parallel axes, means to rotate said frames in opposite directions, means including a plurality of teeth arranged in a line on one of said frames and an anvil on the other of said frames to cooperate to form transverse lines of perforations in superimposed plies of material passing between said frames, jaws mounted on the same frame with said anvil and on opposite sides thereof and arranged to engage each other in front of said anvil, and means to open said jaws before engagement of said anvil by said teeth and to close the same to fold back said webs along each line of perforations made by said teeth.

6. In combination, a narrow platen mounted to rotate about an axis, jaws at opposite sides of said platen, means for urging said jaws together at the front of said platen, a toothed blade movable into and out of engagement with said platen in a part of the path thereof to perforate material extending therebetween, means to open said jaws as the platen approaches a position for engagement by said blade and to release said jaws immediately upon such engagement for folding said material along the line of perforation, and means to separate said jaws after disengagement of said blade from said platen.

7. In combination, a knife mounted to rotate about an axis, an anvil movable to and from a position to cooperate with said knife to perforate material therebetween, jaws pivoted adjacent said anvil to move therewith, means urging said jaws into engagement in front of said anvil, means to open said jaws when said block approaches a position for engagement with said knife and for releasing said jaws, after engagement between said

knife and said block, to fold said material over said knife and remove it therefrom, and means to open said jaws upon separation of said anvil and knife.

5 8. In combination, two parallel shafts, means for rotating said shafts in opposite directions at equal speeds, a frame on each of said shafts, a toothed member on one of said frames, a platen member on the other frame 10 for engagement with said toothed member and means for adjusting one of said members including screws interposed between said member and the corresponding shaft.

9. In combination, two rotatable members, 15 means for rotating said members in opposite directions at the same speed, toothed blades and platen members arranged alternately on said members for perforating, first from one side and then from the other, webs passing between said rotatable members, jaws associated 20 with each of said platen members and urged toward engagement across the face thereof, and means for opening each pair of jaws as the adjacent platen approaches engagement 25 with the corresponding toothed blade on the other rotatable member and permitting the jaws to close after such blade and platen engagement, and for again opening said jaws after separation of the blade and platen.

30 10. In combination, means for perforating superimposed webs at a plurality of points in each of a succession of transverse lines across the web comprising cooperating piercing and anvil members, and means for folding and 35 pressing said webs into a flat fold along each line of perforation concomitantly with the perforating action and alternately in opposite directions, and for swinging the webs back and forth to form a pack in accordance with 40 the direction in which the folds are formed.

11. In combination, a toothed blade, a 45 platen member to cooperate with said blade to perforate along transverse lines superimposed webs passing through the device, means for moving said knife and platen members toward and from each other, folding means associated with said platen member and including jaws for engaging said webs on opposite sides of a line of perforations substantially at the time the perforation is effected and forming a flat fold at said line, and means for effecting relative adjustment 50 between said jaws and said platen member.

12. In combination two frames rotatable 55 about parallel axes, means to rotate said

frames in opposite directions, means including a toothed knife on one of said frames and an anvil on the other of said frames to cooperate to form transverse lines of perforations in superimposed plies, of material 60 passing between said frames, a connection between said knife and the corresponding frame supporting the knife against radial movement but permitting the knife to yield rearwardly with reference to the direction 65 of rotation of the frame, jaws mounted on the same frame with said anvil and on opposite side thereof and arranged to engage each other in front of said anvil, and means to open said jaws before engagement of said 70 anvil by said toothed blade and to close the same to fold back said webs along said line of perforations substantially as soon as the latter is formed.

13. In combination, two parallel shafts, 75 means for rotating said shafts in opposite directions at equal speeds, a frame on each of said shafts, a toothed knife member on one of said frames, a platen member on the other frame for engagement with said knife, means 80 for adjusting one of said members including screws interposed between such member and the corresponding shaft, and threaded into such member, and means for clamping the adjusted member in position including screws 85 extending through slots in said frame and threaded into the adjusted member.

14. In combination, two rotatable members, means for rotating said members in opposite directions at the same speed, toothed 90 blades and platen members arranged alternately on said members for perforating, first from one side and then from the other webs passing between said rotatable members, jaws associated with each of said platen members 95 and urged toward engagement across the face thereof, and means for opening each pair of jaws as the adjacent platen member approaches engagement with the corresponding toothed blade on the other rotatable member 100 and permitting the jaws to close after such blade and platen engagement, and for opening said jaws after separation of the blade and jaw, and means for effecting relative adjustment of said rotatable members around 105 their axes to assure proper engagement of said blades and platen members.

In testimony whereof I have affixed my signature to this specification.

ABRAHAM NOVICK.
